COMBINATION VALVE AND SAFETY PILOT

Raymond P. Flagg, Golden Valley, Minn., assignor to Minneapolis-Honeywell Regulator Company, Minneapolis, Minn., a corporation of Delaware

Application September 9, 1957, Serial No. 682,792

5 Claims. (Cl. 200—61.86)

This invention relates to a combination valve and safety pilot particularly adapted for use in gas burning heating systems. More particularly, the invention relates to a combined, manually-resettable, safety-pilot valve and switch attachment for electrically operated gas valves, such as the one illustrated in John R. Jamieson co-pending application Serial No. 507,552, filed May 11, 1955.

While the combination of a main gas valve, a pilot gas valve and a safety switch that controls the energization of the main valve are broadly well-known in the gas heating field, this invention provides a very compact, inexpensive, and reliable attachment for an electrically operated main or control gas valve. It can convert an electrically operated valve into a single compact unit which provides not only control of the main gas to a furnace but also safety shutdown of the main burner as well as control of the pilot burner, by the pilot valve embodied therein, all without increasing the overall size of the assembly to any great extent.

One of the objects of the invention is to provide an "add on" safety pilot attachment for an electrically operated valve so as to not increase the overall size of the valve too great an amount;

Another object of the invention is to provide a very compact attachment for an electric valve in which a switch and a pilot valve are adapted to be held in closed and opened positions, respectively, by means of a flame responsive control member;

Still another object of the invention is to provide a 100% safety reset, safety pilot attachment for an electrically operated valve, wherein a combined on-off and adjustable flow plug valve are compactly arranged therein, in series with the safety pilot valve.

Still further objects of the invention will become apparent upon reading the following detailed description of the invention in conjunction with the accompanying drawing wherein:

Figure 1 is a vertical sectional view of the invention;

Figure 2 is a vertical end view of the invention, as viewed from the left-hand end thereof in Figure 1 of the drawing and with a portion thereof broken away;

Figure 3 is a side view of the safety pilot portion of the invention;

Figure 4 is a plan view of the invention with portions thereof broken away;

Figure 5 is a sectional view of the switch portion of the invention taken along line 5—5 of Figure 1; and

Figure 6 is a sectional view taken along line 6—6 of Figure 4.

As the details of the electrically operated valve 11 form no part of the invention, the components of the control or main valve will be only briefly described. It consists of a valve body 12 having a threaded inlet 13, a threaded outlet 14, and a valve seat 15 therebetween. A housing 16 is secured to the body 12 and has a main gas control valve 17 pivoted thereon so as to cooperate with the valve seat 15. This valve is adapted to be

2

actuated, through a yoke 18, by a plunger 19 positioned within a solenoid coil 20. Energization of the coil winding causes the plunger to move inwardly of the coil and rock the valve carrying lever on its pivotal connection 5 with the housing 16, to open the valve 17. One end 21 of the coil is connected to a central terminal 22 of a terminal block 23 while the other end 24 of the coil is connected to the terminal 25 (Figure 4).

The terminal block 23 forms a portion of the safety 10 pilot section of the invention that can be added to an electrically operated valve, such as the valve illustrated in the above mentioned Jamieson application and as illustrated in Figure 1 of the drawing. The terminal block 23 is substituted for a conventional terminal block 15 on the cover 16a for the housing 16.

The terminal block comprises a lower casting 26, of Bakelite or any other suitable material and an upper casting 27 of the same material. The two castings are held together and on the cover 16a by means of terminals 25 and 28 at each end of the terminal block. It is to be noted that the terminal members are electrically 20 insulated from the cover 16a by means of rings 29 and washers 30 made of suitable electrically insulating material.

25 The lower casting 26 of the terminal block 23 has a recess 31 and a recess 32 in the upper surface thereof and a bore 33 extending vertically through an end thereof that projects beyond the end of the cover 16a. The upper casting 27 has a recess 34 in the bottom surface 30 thereof and a vertically extending bore 35 passing through the casting in axial alignment with the bore 33 in the lower casting. A flexible contact blade 36 is clamped to the lower casting at one of its ends by the head of the terminal member 22 extending through the lower casting 26 while the other end of the terminal blade 25 extends over the bore 33. An extension 36a of the blade 36 extends into the recess 32 with a fit that prevents rotation of the blade 36 about the terminal 22. The blade 36 also has a transversely extending arm 36b that 40 serves as one contact of the switch controlling the energization of the coil 20. A second contact blade 37 has a fixed end positioned between the castings 26 and 27 with a reverse-bend end portion 37a (Figure 6) that resiliently bears against the terminal 28 to provide electrical connection therewith. Portion 37b has an upwardly struck button portion 37c that is adapted to engage the portion 36b of contact 36 to complete a circuit from the terminal 28 to the coil 20 through the contact blades.

50 Another metallic casting 38 is secured to the terminal block 23 by means of a screw 39 extending through the terminal block and screw threaded into the casting 38. The lower end of the casting 38 is secured to the valve body 12 by means of a plate 40 secured to the casting 55 28 by screws 41 and to the valve body by screws 42. A conical bore 43 extends downwardly from the top of the casting 38 and terminates in a threaded bore 44. A valve seat member 45 is screw threaded into the threaded bore 44 and into sealing engagement with a shoulder formed 60 by a smaller diameter bore 46 extending downwardly from the bore 44 and terminating in a still smaller diameter bore 45 which, in turn terminates in an open sided chamber 47 in the lower right-hand end and side of the casting 38.

65 A plug valve 48 is resiliently held in the bore 43 by means of a leaf spring 49 bearing downwardly on a collar 50 clamped on the plug valve by means of a handle 51 staked in place on the plug valve. The plug valve has an axial passage 53 therein communicating with a radial passage 54 therein which is adapted to register with a passage 55 leading to the outlet fitting 56. A

valve stem 57 fits snugly in the bore 45 and has a valve head 58 at its upper end that engages the valve seat 45 to control the gas flow through the casting 38. The rate of flow through the casting is controlled by a needle valve 59 threaded into the plug valve so as to vary the size of the opening of the bores 53 and 54. Screw 52 seals the passage 53 over the valve 59.

Gas flow to the bore 46 is from a pilot gas inlet 73 through passage 79 (Figure 2) to filter chamber 80 and, from these, through filter 81 and passage 82 to bore 46.

The valve stem 57 extends through a forked end of a pivoted lever 60 and has a spring strain release connection 61 with the lever. At the very bottom of the stem 57, there is an abutment washer 62 thereon retained by a split washer 63 fitting in an annular groove 64 in the bottom of the stem. A valve is adapted to be actuated to its open position by the forked end of the lever 60 moving downwardly and engaging the washer 62 to pull the valve head 58 from the valve seat 45. As can best be seen in Figure 3 of the drawing, the lever 60 has a fixed pivot 65 extending through the plate 40, through upwardly extending ears 68 of the lever 60, and into a boss 66 formed on the inner wall of the casting 38. The lever 60 also has an aperture 60b therein through which a manually operable plunger 67 extends.

The plunger 67 has a split ring abutment shoulder 68 thereon in an annular groove for engagement with the upper surface of the lever 60 near one end thereof and on the same side of the pivot 65 as the valve stem or plunger 57. The stem 67 extends upwardly through a bore 69 in the top wall of the casting 38 and terminates in a head portion 67a that is located in the bore 33 of casting 26 of the terminal block. A spring 70, extending between the upper wall of casting 38 and a split washer 71 located in an annular groove in the stem 67 a short distance from the upper wall, normally biases the stem 67 downwardly away from the contact blade 36. As illustrated in the drawing, the lever 60 is holding the stem of plunger 67 in its uppermost position against the bias of spring 70 to hold the blade 36 out of engagement with blade 37.

A thermocouple energizable electromagnet 72 is mounted in the casting 38 by means of a thermocouple connector member 72a extending through an aperture 73 in the casting and clamped in this position by means of a nut 74 threaded onto the thermocouple connector 72a. The thermocouple magnet unit 72 is of conventional construction and encloses or includes an armature (not shown) that is movable into and out of engagement with an electromagnet (not shown) and so arranged that the armature will be held by the electromagnet when the coil is energized by a thermocouple heated by a pilot burner (not shown). As illustrated in the drawing, a compression spring 75 has the stem 76 of the armature biased downwardly against the other end of the lever 60, thus holding the stem 67 and plunger 57 in their uppermost positions. The spring 75, being much stronger than the spring 70, will force the valve closed and the contact 36 out of engagement with the contact 37 whenever the magnet is incapable of holding the armature against it. Since the coil 20 of the solenoid plunger that actuates the main valve is controlled by the switch blades 36 and 37, it is obvious that the valve 17 can not open as long as the contact blade 36 is separated from the contact blade 37. It is thus seen that the arrangement of the elements of both the valve body and of the safety pilot attachment for the valve, as illustrated in the drawing, are all in a "shut-down" condition.

In order to place the control apparatus for the heating system in which it is installed in operation, a manually operable reset button 77 may be depressed in the bore 33 so that the lower end of the button 77 engages contact blade 36 and moves the plunger 67 downwardly against the lever 60 to, thereby, lift the armature stem 76 into engagement with the electromagnet and to simultaneously

lift the valve stem 57 out of engagement with the valve seat 45. The reset button 77 has a lateral extension 77a that extends downwardly from the portion that engages the blade 36 so as to engage the blade 37 at substantially the same time that it engages the blade 36. As the button 77 engages the two blades in its forward movement, the plunger 67 maintains the two blades in separated relationship so that as the valve is moved to its open position and the armature is reset, no current can flow to the coil 20. When the electromagnet has become energized due to the fact that the pilot burner has been ignited, releasing of the reset button 77 will permit the contact blade to lift the reset button 77, due to the bias placed thereon in the inward movement of the reset button, and to cause the contact 37c to lift up into engagement with the portion 36b on the contact blade 36, the contact blade 36 being in its normal unflexed position due to the fact that the plunger 67 is lowered under the compression of spring 70. It is thus seen that only if the armature is energized so as to hold the spring 75 depressed, is it possible for the switch blades 36 and 37 to complete a circuit to the solenoid 20. The circuit to the main valve coil 20 is completed through a lead wire (not shown) from the terminal 65, through a room thermostat (not shown) and through a lead wire (not shown) from the thermostat back through a power source to the terminal 28.

The main valve will thus be opened only if the room thermostat is calling for heat and only as long as there is a flame present at the pilot burner keeping the thermocouple heated to the extent necessary to energize the electromagnet of the unit 72.

With the main burner in operation, should there be a pilot flame failure, the electromagnet will become de-energized causing the spring 75 to close the pilot valve and to break the contact between the blades 36 and 37 and thereby close the main valve. This causes 100% safety shutdown of all gas being supplied to the heating installation.

While I have illustrated the preferred embodiment of the invention, it is deemed to be obvious to those skilled in the art that modifications may be made therein without departing from the spirit of the invention. Therefore, the scope of the invention is to be determined from the appended claims.

I claim for my invention:

1. A combination main valve and pilot valve and switch comprising a main valve, a pilot valve, a first plunger for actuating said pilot valve, a pivoted lever operably engaging said plunger, means biasing said plunger in a direction to open said pilot valve, stronger means for biasing said lever in a direction to close said pilot valve, condition responsive means capable of holding said lever in but incapable of moving it to valve open position, a pair of contact blades each having a fixed end and a free end which normally engages the free end of the other blade, a second plunger normally flexing a first of said blades out of engagement with the second blade, and manually operable means movable into engagement with both of said blades to simultaneously move the free ends thereof and the two plungers to open said pilot valve while holding said free ends separated, said manually operable means being movable to its inoperative position and said second blade being movable into contact with said first blade under the bias of the second blade upon release of said manual means when the condition responsive means is energized.

2. In combination with an electrically operated control valve, a switch and pilot valve adaptor for the control valve comprising a pilot valve housing having an inlet and an outlet with a valve seat therebetween, a pilot valve operable with said seat, a first plunger for actuating said pilot valve, a pivoted lever operably engaging said plunger, means biasing said plunger in a direction to open said valve, stronger means for biasing said lever in a direction to close said valve, condition responsive means

capable of holding said lever in but incapable of moving it to valve open position, a pair of contact blades each having a fixed end and a free end which normally engages the free end of the other blade, a second plunger normally flexing a first of said blades out of engagement with the second blade, manually operable means movable into engagement with both of said blades to simultaneously move the free ends thereof and the two plungers to open said pilot valve while holding said free ends separated, said manually operable means being movable to its inoperative position and said second blade being movable into contact with said first blade under the bias of the second of said blades upon release of said manual means when the condition responsive means is energized, and a terminal block partially overlying and secured to said pilot valve housing and partially overlying said control valve and being securable thereto to hold both valves in assembled relationship.

3. A combination switch and pilot valve adaptor for an electrically operated main valve comprising a pilot valve housing having an inlet and an outlet with a valve seat therebetween, a pilot valve cooperable with said seat, a first plunger for actuating said pilot valve, a pivoted lever operably engaging said plunger, means biasing said plunger in a direction to open said valve, stronger means for biasing said lever in a direction to close said valve, condition responsive means capable of holding said lever in but incapable of moving it to valve open position, a pair of contact blades each having a fixed end and a free end which normally engages the free end of the other blade, a second plunger normally flexing a first of said blades out of engagement with the second blade, and manually operable means movable into engagement with both of said blades to simultaneously move the free ends thereof and the two plungers to open said pilot valve while holding said free ends separated, said manually operable means being movable to its inoperative position and said second blade being movable into contact with said first blade under the bias of the second of said blades upon release of said manual means when the condition responsive means is energized.

4. A combination switch and pilot valve adaptor for an electrically operated main valve comprising a pilot valve housing having an inlet and an outlet with a valve seat therebetween, a pilot valve cooperable with said seat, a first plunger for actuating said pilot valve, a flow adjusting valve concentric with said valve seat and plunger, a

5 pivoted lever operably engaging said plunger, means biasing said plunger in a direction to open said valve, stronger means for biasing said lever in a direction to close said valve, condition responsive means capable of holding said lever in but incapable of moving it to valve open position, a pair of contact blades each having a fixed end and a free end which normally engages the free end of the other blade, a second plunger normally flexing a first of said blades out of engagement with the second blade, and manually operable means movable into engagement with both of said blades to simultaneously move the free ends thereof and the two plungers to open said pilot valve while holding said free ends separated, said manually operable means being movable to its inoperative position and said second blade being movable into contact with said first blade under the bias of the second of said blades upon release of said manual means when the condition responsive means is energized.

20 5. A combination switch and pilot valve adaptor for an electrically operated main valve comprising a pilot valve housing having an inlet and an outlet with a valve seat therebetween, a pilot valve cooperable with said seat, a first plunger for actuating said valve, a pivoted lever operably engaging said plunger, means biasing said plunger in a direction to open said valve, stronger means for biasing said lever in a direction to close said valve, condition responsive means capable of holding said lever in but incapable of moving it to valve open position, a pair of contact blades each having a fixed end and a free end which normally engages the free end of the other blade, a second plunger substantially parallel to said first plunger and normally flexing a first of said blades out of engagement with the second blade, manually operable means movable into engagement with both of said blades to simultaneously move the free ends thereof and the two plungers to open said pilot valve while holding said free ends separated, said manually operable means being movable to its inoperative position and said second blade being movable into contact with said first blade under the bias of the second of said blades upon release of said manual means when the condition responsive means is energized, and on a terminal block overlying and secured to said adaptor and having a portion thereof extending beyond said adaptor to overlie and to secure said adaptor to an electrically operated valve.
